UNITED STATES PATENT OFFICE.

JOSEPH DAVY, OF OAKLAND, CALIFORNIA.

HASP-LOCK.

SPECIFICATION forming part of Letters Patent No. 771,814, dated October 11, 1904.

Application filed December 31, 1902. Serial No. 137,301. (No model.)

To all whom it may concern:

Be it known that I, JOSEPH DAVY, a citizen of the Republic of France, residing at Oakland, in the county of Alameda and State of California, have invented certain new and useful Improvements in Hasp-Locks, of which the following is a specification.

My invention relates to locks, and more particularly to that class of such devices in which a hasp-fastener and a lock are combined in the same structure.

In the patent granted to me January 2, 1900, No. 640,637, I provided the lock portion with two reciprocating spring-pressed pins or plungers, one of which was adapted to be operated by the key and to in turn operate the other plunger and withdraw the locking pin or bolt which formed a part thereof; but I have discovered that by the use of a different form of key I can dispense with one of the plungers and operate the other plunger and lock with the key direct, thereby simplifying the construction and making a safer and more desirable lock.

The accompanying drawings illustrate the present invention and form a part hereof, the same reference character indicating the same part in each of the views in which it occurs.

Figure 1 is a plan view of a lock embodying my invention, the hasp being shown closed and locked in full lines and unlocked in dotted lines. Fig. 2 is a similar view, the hasp being broken away and the top of the lock removed. Fig. 3 is a view in longitudinal side elevation of the construction represented by Fig. 1. Fig. 4 is a sectional view showing the position which the parts of the lock occupy when the key is inserted. Fig. 5 is a similar view showing the key after it has been turned preparatory to withdrawing the bolt. Fig. 6 is a similar view with the key forced in and the bolt withdrawn. Figs. 7 and 8 are respectively a side elevation and an end view of the bolt receptacle or casing. Figs. 9 and 10 are similar views of the bolt. Fig. 11 is a partly-broken side view of the key.

Referring more particularly to the drawings, 1 indicates the shell or case of the lock, which shell or case is secured to a plate 2 in any suitable manner, preferably by means of

two pins or projections 3, extending through perforations in the plate and headed or riveted therein. The aforesaid shell 1 is preferably made cylindrical and its bottom or inner end is provided with an oblong central cavity 4, 55 from the bottom of which at one end projects a pin or guide 5 for the reception of a hollow-stemmed key 6, provided with bits 18. Seated within this shell above the cavity therein and diametrically opposite the pin 5 is a bolt receptacle or casing 7. This casing is also oblong in cross-section and extends from the bottom of the shell 1 above its said cavity 4 to the plate 2 and is clamped therebetween when the plate is riveted to the shell. A thin flat projection or leg 8 extends from the lower end of the casing 7 and fits in the recess or cavity 4 to assist in holding said casing from turning when the lock is being operated. The casing 7 is further provided with a longitudinal bore 9, 60 within which is placed a longitudinally-movable bolt 10. The side of the casing 7 adjacent to the guide-pin 5 is slotted longitudinally, as at 11, into the bore 9 and notched along one edge to form stops or wards 12, the bottom of the notches being preferably inclined, as shown at 13. The bolt comprises a pin-like locking portion, (marked 10,) a cylindrical central portion 14, which fits the bore 9 of the casing 7 and from which the part 10 65 projects, and a guide-strip 15. The pin 10 is of a less diameter than the central portion 14, and thereby forms a shoulder 16, which engages with the plate 2 when the bolt is projected outward into its locking or operative 70 position. The guide-strip 15 extends from the shoulder 16 along one side of the central portion 14 and projects below the end thereof and terminates in a step 17. It fits within the slot 11 of the bolt-casing and prevents the 75 bolt from rotating on its axis while being operated and holds the step 17 at the bottom in a line with the bits 18 of the key 6 after they have passed the wards 12 and the key is in position to be forced inward to withdraw the 80 bolt, the step being at such a distance of the end ward as to permit the entrance of the bit of the key.

A spring 19 is placed in the bore 9 below the bottom of the central portion of the bolt 100

and rests upon the bottom of the recess or cavity 4. This spring normally forces the bolt outward into its locking position and is compressed to allow the withdrawal of the 5 bolt by forcing the key inward after it has been partially rotated to cause its bits to pass the wards of the bolt-casing. This inward movement of the key can only occur when the key has been rotated sufficiently to permit a 10 fin or projection 20 on its stem to enter the slot or elongated portion of the keyhole 21, formed for the passage of the bits 18. The fin 20 is preferably formed diametrically opposite these wards, so that the key must be 15 given a half-turn before it can be pushed in to withdraw the bolt.

The plate 2 is adapted to be secured in position by means of screws in the ordinary manner and has upon its exterior a substantially 20 U-shaped staple, or staple-like projection 22, provided with annular ends 23. One leg of this staple is formed upon or secured to the plate 2 and the other one is directly above the first leg and at such a distance there- 25 from as to admit of a locking-bar 24 being mounted so as to swing between them. The bar 24 pivots upon and around a hollow bolt 25, within which is formed the keyhole 21, and which bolt passes also through the annular 30 ends 23 of the staple. As shown, the hollow bolt has a flange 26 at its outer end, which is seated on the ring of the upper leg of the staple, and at its inner end it is rigidly secured to the plate 2. The lower leg of the staple is 35 provided with a perforation 27, which extends through the plate 2 and through which perforation the pin portion 10 of the locking-bolt projects to prevent the bar 24 being swung into its releasing position, which is all 40 that is necessary when the box or other receptacle to which the lock is applied is empty; but when it is desired to more securely fasten the lock the end 10 is caused to enter either one of two holes 28, which are formed in an 45 expanded portion 29 of the bar, the same being adapted to be swung between the legs of the staple until either hole 28 registers with the hole 27 in the lower leg.

The lower leg of the staple 22 is of sub- 50 stantly the same thickness as the hasp, (herein marked 30,) which it is designed to receive, so that when the hasp is turned down with its slot 31 fitting over the U-shaped staple the locking-bar 24 can be swung cross- 55 wise of the legs of the staple and will thereby prevent the removal of the hasp. The bar 24 is pivotally mounted somewhat off its center, and therefore has one end longer than the other, which keeps it from passing between 60 the legs of the staple at the closed end. It is understood that the hasp 30 is flexibly secured at one end to one portion, as 32, of the receptacle to which it is applied, while the lock is secured to another part, as 33.

65 In operating my improved lock when it is

only desired to give it what may be called "partial security" the locking-bar is turned into alinement with the legs of the staple on the lock, and the hasp is thrown down over the same. The bar is then turned laterally 70 to one side or the other, which will cause the end between the legs to be moved from over the bolt and release the same, so that the spring can force it outward. It will now be impossible to return the bar to the required 75 position for releasing the hasp until after the bolt has been forced in, and thus is obtained ordinary security; but when it is desired to more securely fasten the bar against being returned to its opening position the perforated 80 end is swung around until the bolt can enter one of the perforations, in which position it will be impossible to withdraw the bolt by any means except by inserting the key into the keyhole. After the key has been inserted 85 and has engaged the shoulder formed by the juncture of the shell 1 and the cavity 4 it is given a partial rotation until its fin will enter the bit-slot of the keyhole and then it is forced inward, which causes one of the bits 90 of the key, preferably the end one, to engage with the step on the inner end of the bolt and force the bolt inward against the tension of its spring. In this position the bar can be turned to lock or unlock the hasp, after which 95 the key can be removed from the lock by releasing it and letting the spring force it out until the fin is above the casing, when a partial rotation will bring the bits into register with the bit-slot and permit the removal of 100 the key. This lock, it will be observed, is capable of the same general application as that of my previous patent aforementioned. Thus, for example, it is well adapted for use on boxes and chests of every description, 105 packing and shipping cases, gates, freight-car doors, &c.

I have shown and described herein what I consider the simplest and cheapest form of my improved lock; but it is evident that many changes can be made in the same without departing from the fundamental principle of my invention. For instance, the number, arrangement, and relative direction of the bits of the key and coacting parts of the lock can 110 be varied indefinitely, and the lock may be made much more complicated, if deemed desirable. I therefore reserve the right to make all such alterations or modifications as come within the scope of my invention. 115

Having described my invention, I claim—

1. A lock comprising a shouldered shell provided with an opening therein, a bolt-casing located within the shell and out of alinement with the opening, a bolt slidably retained within the casing, wards formed on the bolt-casing, a key receivable in the shell through the opening therein, the key adapted to successively engage the shoulder, the bolt-casing and the bolt respectively. 125 130

2. A lock comprising a shell having a key-aperture therein, a bolt-casing stationarily located within the shell and out of alinement with the key-aperture, a bolt movably located within the casing, wards formed on the casing, a key receivable in the shell, bits and a fin on the key, the bits intermeshing with the wards on the casing, the fin engaging the wall of the key-aperture to retain the bits in staggered relation to the wards, one of the bits adapted to engage and operate the bolt, the fin receivable within the key-aperture to guide the key.

3. In a lock, the combination with a shell, of a slotted bolt-casing located therein, a bolt movably retained within the casing, one wall of the slotted bolt-casing provided with a plurality of wards, the remaining wall of the slot being imperforate and a key receivable within the shell, the key provided with bits adapted to intermesh with the wards and engage the bolt.

4. A lock comprising a longitudinally-movable bolt, means for normally retaining the bolt in locked position, a key adapted to engage the bolt, a guide for the key, the bolt so located with respect to the key that the latter after its insertion into the lock must be turned before being forced inward to release the bolt.

5. In a lock, the combination with a shouldered slotted shell, of a bolt and a key provided with bits, the key receivable in the shell through the slot, the bits adapted to engage the shoulder in the shell, the key adapted to engage the bolt when moved out of engagement with the shouldered shell.

6. In a lock, a bolt-receptacle slotted upon one side, a longitudinally-movable bolt in the receptacle provided with a guide-strip that fits within the slot thereof, the inner end of the guide-strip being extended and provided with a step, and means for moving the bolt inward, substantially as described.

7. In a lock, a bolt-receptacle provided with means for preventing its movement and slotted longitudinally on one side, one side of the slotted portion being provided with wards, and a longitudinally-movable bolt in the receptacle having a guide that fits in the slot and is extended at the inner end to form a step for the engagement with a key, substantially as described.

8. In a lock, a recessed case, a bolt-receptacle therein, one side of which is slotted longitudinally and provided with a thin flat projection for fitting in the recess of the case, and a longitudinally-movable bolt in the receptacle having a guide that fits in the slot thereof and carries a step for engagement with a key, substantially as described.

9. In a lock, a recessed case, a key-guide projecting from the bottom of the recess therein, a longitudinally-slotted bolt-receptacle, and a longitudinally-movable bolt in the receptacle having a guide which fits within

the slot thereof, the inner end of the guide being extended and provided with a step which lies adjacent to said key-guide, substantially as described.

10. In a lock, a plate, a case secured thereto the bottom of which is recessed and provided with a key-guide, a longitudinally-slotted bolt-receptacle engaged at its ends by the plate and the case and having a flat projection which fits in the recess of the case, a bolt in the receptacle provided with a guide which fits in the slot of the bolt-receptacle, the inner end of the guide being extended and provided with a step, and a spring between the inner end of the bolt and the bottom of said recess, substantially as described.

11. In a lock, a plate, a case secured thereto the bottom of which is recessed, a guide-pin in the bottom of the recess of said case, a bolt-receptacle between the plate and the bottom of the case, one side of which is slotted and provided with wards, a longitudinally-movable bolt in the receptacle, one end of which is reduced to form a shoulder for engaging with the plate and the central portion of which has a guide, the inner end of said guide being extended and provided with a step, said step being within said recess and normally lying at such a distance from the innermost ward as to permit the insertion of the bit of a key therebetween, whereby the bolt may be forced inward, and a spring under the inner end of the bolt, substantially as described.

12. In a lock, a case having a keyhole and a bolt-hole, one side of the keyhole being extended laterally for the passage of a key provided with bits and a laterally-projecting fin, a bolt-receptacle in the case, one side of which is slotted longitudinally and provided with wards, a spring-pressed longitudinally-movable bolt in the receptacle, the outer end of which is reduced to form a shoulder and to let said end project through the bolt-hole and the main portion of which is provided with a guide that fits in the slot of the receptacle and has its inner end provided with a step, said step registering with said slot and being adapted to be engaged by one of the bits of said key, the slot in said receptacle being so situated relatively to the bit-slot of the keyhole that said key must be partially turned after insertion into the case before it can be forced inward to withdraw the bolt, substantially as described.

13. In a lock, a plate having a substantially U-shaped projection the free ends of which are provided with an elongated keyhole and the inner leg of the projection with a bolt-hole, a locking-bar mounted to swing between the legs of said projection, a case secured to the inner side of the plate, the bottom of which is provided with a key-guide, a longitudinally-slotted bolt-receptacle in the case, and a spring-pressed longitudinally-movable bolt in said receptacle the outer end of which projects through the bolt-hole and the inner end of

which has a step that registers with the slot of the receptacle, said slot and the elongation of the keyhole being so located relatively to each other that a key provided with bits and a fin must be given half a turn after being inserted in the case before it can be forced farther inward to withdraw the bolt, substantially as described.

14. The combination in a lock, with a key provided with bits and a fin, the bits and fin located laterally and transversely apart from

one another, of a key-barrel, a shouldered shell, a bolt in the casing, the bits adapted to engage the shoulder and the fin adapted to engage the key-barrel to prevent the entrance of the key and the movement of the bolt until the key is partially rotated. 15
